UNITED STATES PATENT OFFICE.

GEORGE DAVIS, OF CINCINNATI, OHIO.

DESIGN FOR A FLOUR-SAFE.

Specification forming part of Design No. 5,224, dated August 22, 1871.

To all whom it may concern:

Be it known that I, GEORGE DAVIS, of Cincinnati, in the county of Hamilton and State of Ohio, have invented and produced a new and original Design for a Flour-Safe, of which the following is a specification:

The nature of my design is fully represented in the accompanying illustration, to which reference is made.

I claim as my invention—
The design for a flour-safe, as shown.
In testimony of which invention I hereunto set my hand.

GEORGE DAVIS.
